(57) **CLAIM**

The ornamental design for a handle for medical device, as shown and described.

DESCRIPTION

FIG. 1 is a perspective view of a handle for medical device showing the new design.

FIG. 2 is a front view thereof, a rear view thereof being a mirror image of the front view.

FIG. 3 is a right side view thereof, a left side view thereof being a mirror image of the right side view.

FIG. 4 is a top view thereof; and,

FIG. 5 is a bottom view thereof.

The broken lines in the figures illustrate unclaimed environment only and form no part of the claimed design.
